BOW-MOUNTED STEERING CONSOLE FOR BOATS

Joseph G. Cox, Jr., 2611 Gilmer Road,
Longview, Tex. 75601

Filed Mar. 2, 1970, Ser. No. 21,682

Term of patent 14 years

Int. Cl. D12—99

U.S. Cl. D71—1

FIG. 2

FIG. 1 is a side perspective view of a bow-mounted steering console for boats showing my new design; and FIG. 2 is a front perspective view thereof.

The broken line disclosure of the forward portion of a boat is shown in FIG. 1 for illustration purposes only.

I claim:

The ornamental design for a bow-mounted steering console for boats, as shown and described.
